CLAIM

The ornamental design for an ice machine, as shown and described.

DESCRIPTION

FIG. 1 is a front, top perspective view of a first embodiment of an ice machine, showing our new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 2;

FIG. 10 is a front, top perspective view of a second embodiment of FIG. 1, the only difference being the configuration on the front surface, it being understood that all other surfaces are the same as those of the first embodiment; and,

FIG. 11 is a front, top perspective view of a third embodiment of FIG. 1, the only difference being the configuration on the front surface, it being understood that all other surfaces are the same as those of the first embodiment.

The dashed broken lines in the figures illustrate portions of the ice machine that form no part of the claimed design. The dash dot dash broken lines in FIGS. 2 and 9 are for the purpose of illustrating the enlarged view indicators and form no part of the claimed design.
